UNITED STATES PATENT OFFICE.

ARCHIE HUGH STRONG, OF FLUSHING, NEW YORK, ASSIGNOR TO MASTER DOMESTIC REFRIGERATING COMPANY, INC., OF QUEENS COUNTY, NEW YORK, A CORPORATION OF NEW YORK.

REFRIGERATING APPARATUS.

Application filed April 9, 1926. Serial No. 100,812.

This invention relates generally to refrigerating apparatus, and particularly to refrigerating apparatus of the automatically controlled absorption type.

5 Refrigerating apparatus of the type mentioned are generally characterized by the provision of a generator within which a refrigerating medium, commonly an aqueous solution of ammonia, is heated to transform 10 the ammonia into a gas, which is passed into and condensed within a suitable condenser from which the condensed refrigerant, namely, ammonia, is directed into a suitable evaporator to be therein transformed, upon 15 the completion of the heating period, back into a gas which is returned to the generator and absorbed by the liquid remaining therein at the completion of the heating period.

One of the chief difficulties heretofore 20 encountered in connection with refrigerating apparatus of this type, resides in the fact that complicated control devices have been employed to govern the operation of the apparatus with the result that such devices 25 were likely to get out of order and could not, therefore, be relied upon to effect proper and uninterrupted functioning of the apparatus.

An object of this invention is to overcome 30 the above mentioned objections and thus provide a generally improved apparatus of the absorption type which is simple in construction, reliable in operation and at the same time inexpensive to manufacture as well as 35 economical to maintain.

Other objects and certain advantages of 40 the invention will become apparent from the following description, when taken in connection with the accompanying drawings in

45 Figure 1 is a view showing the several co-operative elements of the apparatus in their respective positions at the beginning of the heating period.

50 Figure 2 is a view showing the relative positions of the several switch elements immediately after the completion of the heating period.

55 Figure 3 is a view similar to Figure 2 showing the relative positions of the several elements at or about the time the lowest temperature in the evaporator has been attained.

Figure 4 is a transverse sectional view 55 taken on the line 4—4 of Figure 3.

Referring to the drawings, a suitable generator 10 is connected by means of a pipe 11 to a water trap 12, of conventional design, from which a pipe 13 leads to a condensing coil 14, the condensing coil 14 being 60 in turn connected by means of a pipe 15 through which the condensed liquid will flow by gravity to an evaporator 16.

The coil 14 is arranged within a receptacle or condensing reservoir 18 provided with a 65 suitable overflow or outlet pipe 19, which in turn is connected to the outlet end of a cooling tube 20 arranged within and extending through the generator 10. A water supply pipe 23 is arranged to supply water to the condensing reservoir 18 or to the cooling tube 20, through pipes 24 and 25, respectively, which are connected to a suitable valve mechanism 27 adapted to be actuated, as will hereinafter appear, so as to direct the 70 water supply either to the condensing reservoir 18 or to the cooling tube 20.

Within the generator 10, is arranged a 75 suitable electrical heating element in the form of a resistance unit 28, from which conductors 29 lead to a pair of contacts 30 which form part of a circuit closer or switch mechanism 33. This switch mechanism comprises a frame 34 within which is journaled a shaft 35 carrying rigidly thereon a toothed 80 segment 36 and a lever 38, the latter of which is connected, by means of a link 39, to a lever 40 suitably pivoted at one end to a valve rod 43 secured to a tubular, slid able 85 valve 44, provided with ports 45 and 46, and arranged to reciprocate within the valve casing or housing 47. Upon the shaft 35 is journaled an arm 50 to which is pivotally connected a pawl 51, provided at its free end with a pin 52 and connected, by means of a tension spring 53, to the shaft 35. The arm 50 is connected by means of a link 54 to a lever 55, which in turn is pivoted to a suitable support or housing 56, with which a compression spring 57 is associated. This 90 compression spring is adapted to engage a lever 58, which is pivotally connected at one end to the housing 56 and linked at its other end to the lever 55 by means of a link 59.

The spring 57 cooperates with the lever 58 to move the arm 50 from its uppermost pos- 95 100 105

tion to its lowermost position, the latter position being shown in Figure 3. The arm is moved in an opposite direction, from its position shown in Figure 3 to its uppermost 5 position, through the instrumentality of a sylphon bellows 60 which, by means of a tube 63, is connected to a suitable thermostat 64 associated with the evaporator 16.

To the toothed segment 36 is suitably connected 10 a strip of insulating material 65 which carries at its ends a pair of resilient contact fingers 66, provided at their respective free ends with contacts 67, adapted to engage the fixed contacts 30, which are carried by and suitably insulated from the frame 34. The resilient contact fingers 66 are suitably connected to a pair of conductors 68, so that when the contacts 67 engage the contacts 30, a circuit from a suitable 20 source of electrical energy, not shown, will be closed through the heating unit 28.

Within the generator 10 there is arranged a suitable thermostat 69 which, by means of a pipe 70, is connected to a sylphon bellows 25 73 provided with a movable pin 74, adapted to engage an adjustable screw-pin 75 carried by an arm 76 which is pivotally connected at one end to the housing of the sylphon bellows 73, as shown at 77, and is connected at its other end, by means of a link 30 78 to a release arm 79 which is pivoted at 80 and is adapted to engage the pin 52, carried by the pawl 51, to move the pawl 35 out of engagement with the toothed segment 36.

A by-pass pipe 89 is connected with the evaporator at or near the bottom thereof. This by-pass pipe is connected to the pipe 13 and at its junction therewith, a valve 90 is provided. By means of the valve 90 communication 40 between the pipe 13 and pipe 89 may be established and communication between the pipe 13 and condensing coil 14 simultaneously severed. The function of the by-pass pipe is to provide communication 45 between the generator and the bottom of the evaporator 16 so that any liquid, such as water, that may collect in the evaporator from time to time and fail to return, as a 50 gas or vapor, to the generator during the evaporation period may be directed back into the generator when desired. In order to effect this return of liquid, the heating period 55 is carried out, as in the normal course of operation, and upon the completion of the heating period, the valve 90 is so rotated as to sever communication between the pipe 13 and condenser coil 14 and establish 60 communication between the pipe 13 and pipe 89. With communication established between the pipes 13 and 89, such liquid as has collected within the evaporator 16 is siphoned back into the generator 10 due to 65 a fall in pressure therein which is caused by the cooling action of the water supply from

the pipe 23 upon the generator contents, the siphoning action being augmented by any pressure that may be set up within the evaporator due to the collection of gas therein above the liquid level. This scavaging 70 operation may be carried out from time to time, for example every thirty to sixty days depending upon operating conditions, and is continued only so long as is necessary to remove the undesirable liquid contents from 75 the evaporator after which the valve 90 is so rotated as to sever communication between the pipes 13 and 89 and establish communication between the pipe 13 and condenser coil 14 whereupon the evaporating period is 80 completed in the normal operation of the apparatus.

Assuming that the generator 10 carries an aqueous solution of ammonia and that the several cooperative elements of the circuit closer 33 have just been moved to the positions shown in Figure 1, the operation of the apparatus is as follows: Water flows from the supply pipe 23 into and through the condensing reservoir 18, inasmuch as the 85 slide valve 44 is so positioned as to establish communication between the pipes 23 and 24 and through the port 45. The aqueous solution of ammonia within the generator 10 is being heated for the reason that the electrical circuit through the resistance unit 28 is closed. As a result of such heating, the ammonia is transformed into gas and this 90 gas passes from the generator 10 through the pipe 11 into the trap 12 which, as above explained, so functions as to collect and trap any water that may condense therein from vapor arising out of the generator 10. As the gaseous ammonia passes into the 95 trap 12 it is directed therefrom into the condensing coil 14 through the pipe 13. The condensing coil 14, being maintained at a relatively low temperature due to the constant flow of water through the reservoir 18 functions to condense the gas into a liquid which flows into the evaporator 16 through the pipe 15. The heating period is maintained for a certain length of time, say two hours, depending upon varying 100 conditions. During the heating period the sylphon bellows 73, in response to the action of the thermostat 69 caused by a gradual rise in temperature within the generator 10 as the ammonia is evaporated or driven off from the water, forces the pin 74 outward 105 against the pin 75, and moves the arm 76 against the influence of the tension spring 85 so as to move the arm 79 about its pivot 80. In the movement of the arm 79, the pin 52 of the pawl 51 is lifted by the arm 79 110 until the pawl 51 is released from its locking engagement with the toothed segment 36, whereupon the contact arms 66, due to their 115 having been more or less flexed during the heating period, act to quickly open the cir- 120 125 130

cuit of the heating element 28 and to move the toothed segment 36 and the arm 38 in a clockwise direction, as viewed in Figure 1, which movement is augmented or facilitated by the action of gravity upon these elements and is continued until they have reached their lower positions, shown in Figures 2 and 3. Inasmuch as the valve 44 is operatively connected to the lever 38 it follows that as the toothed segment 36 and lever 38 are moved, as above described, the valve 44 is simultaneously moved from its uppermost position to its lowermost position whereupon the supply of water from the supply pipe 23 is cut off from the condensing reservoir 18 and is diverted through the valve 44, port 46, and pipe 25 into the cooling tube 20 of the generator from which it flows into the waste pipe 19.

Immediately upon opening the circuit through the heating element 28, the liquid, mostly water, remaining within the generator 10, begins to cool, and as the temperature within the generator drops, the thermostat 69 is so acted upon as to permit the tension spring 85 to move the arm 76 gradually in a counter-clockwise direction about its pivot 77, with the result that the arm 79 is simultaneously moved in a corresponding direction well out of engagement with the pin 52 carried by the pawl 51. As the temperature within the generator 10 drops and the pressure therein correspondingly falls, the liquid refrigerant within the evaporator 16 is transformed into a gaseous state and the gas now flows through the pipe 15, cooling coil 14, pipe 13, trap 12, and pipe 11, back into the generator 10, wherein it is absorbed by the liquid remaining therein.

As soon as evaporation starts, the temperature of the evaporator 16 begins to fall, and in a relatively short period, say two hours after evaporation begins, the minimum temperature, for example 5° F. is reached. As a result of this drop in temperature, the thermostat 64 is so acted upon as to permit the projecting pin 86 of the sylphon bellows 60 to recede under the influence of the compression spring 57, which now cooperates with the lever 55 and the lever 58 so as to swing the arm 50 in a clockwise direction about the shaft 35 from its uppermost position to its lowermost position, the latter being shown in Figure 3. The minimum temperature attained by the evaporator 16 remains unchanged for a relatively long period of time, for example, about 10 hours, after which a slow rise in temperature of the evaporator 16 occurs and continues for a relatively long period of time, for example, about 10 hours, at the expiration of which time the temperature of the evaporator will have risen from a minimum to, for example, approximately 35° F. During this rise in

temperature the thermostat 64 is so acted upon as to move the pin 86 of the sylphon bellows 60 up against the arm 58, thus overcoming the influence of the spring 57 and causing the arms 58 and 59 to move from their respective positions, shown in Figure 3, to their positions shown in Figure 1, and as a result of these movements the toothed segment 36, by reason of its engagement with the pawl 51 carried by the arm 50, is correspondingly moved, whereby the contacts 67 are moved into engagement with the contacts 30, thereby closing the circuit through the heating element 28 so that another cycle of operation is started. As the segment 36 is moved from its position shown in Figure 3 to circuit closing position, shown in Figure 1, the shaft 35 is rotated in a counter-clockwise direction, and as a result of such rotation the arm 38 is so moved as to move the valve 44 from its position shown in Figure 2 to its position shown in Figure 1, whereby the water supplied to the generator 10 is cut off and circulation is again established through the condensing reservoir 18, as hereinbefore explained. During the heating period just described as having now begun, the temperature within the evaporator 16 continues to rise, reaching a maximum at or about the time the circuit is again opened through the resistance element 28. As a result of this further rise in temperature the segment 36 is moved from a position at which contact is made to such a position as will flex the spring contact members 66, with the result that they are put under tension and will quickly open the circuit at the completion of the heating period, with a snap action, as previously explained. During the continued movement of the toothed segment 36 whereby the spring contact arms 66 are flexed, the valve 44 will continue to rise within the housing 74 but this further movement is accommodated for by enlargement of the valve port 45.

Having thus described certain embodiments of the invention what is claimed is:

1. A refrigerating apparatus comprising a generator for a refrigerant, an evaporator, periodically operated means for heating the contents of the generator, means for condensing evaporated refrigerant, means for cooling the contents of said generator, control means including a pair of control members, means for locking said members together, means responsive to varying conditions within the evaporator to move said members simultaneously whereby the heating means is rendered operative, and means responsive to varying conditions within the generator to unlock one of said members from the other whereby one of said members may be moved to render the heating means inoperative.
2. A refrigerating apparatus comprising a generator for a refrigerant, an evaporator,

- periodically operated means for heating the contents of the generator, means for condensing evaporated refrigerant, means for cooling the contents of said generator, control means including a pair of control members, means for locking said members together, means responsive to varying conditions within the evaporator to move said members simultaneously whereby the heating means is rendered operative, means responsive to varying conditions within the generator to unlock one of said members from the other, and means for quickly moving one of said members when unlocked to render the heating means inoperative. 10
3. A refrigerating apparatus comprising a generator for a refrigerant, an evaporator, periodically operated means for heating the contents of the generator, means for condensing evaporated refrigerant, means for cooling the contents of said generator, control means including a pair of control members, means for locking said members together, means responsive to varying conditions within the evaporator, means controlled by said responsive means to move said members simultaneously whereby the heating means is rendered operative and to move one of said members into position to be locked to the other member after unlocking, and means responsive to varying conditions within the generator to unlock said members whereby one of said members may be moved to render the heating means inoperative. 20
4. A refrigerating apparatus comprising a generator for a refrigerant, an evaporator, periodically operated means for heating the contents of the generator, means for condensing evaporated refrigerant, control means including a pair of control members, means for locking said members together, means responsive to varying conditions within the evaporator to move said members simultaneously whereby the heating means is rendered operative, means responsive to varying conditions within the generator to unlock one of said members from the other whereby one of said members may be moved to render the heating means inoperative, and means controlled by said responsive means for periodically cooling the contents of the generator. 30
5. A refrigerating apparatus comprising a generator for a refrigerant, an evaporator, periodically operated means for heating the contents of the generator, means for cooling the contents of said generator, control means including a pair of control members, means for locking said members together, means responsive to varying conditions within the evaporator to move said members simultaneously whereby the heating means is rendered operative, means responsive to varying conditions within the generator to unlock one of said members from the other whereby one of said members may be moved to render the heating means inoperative, and means controlled by said responsive means for periodically cooling the contents of the generator. 40
- lock one of said members from the other whereby one of said members may be moved to render the heating means inoperative, and means periodically functioning to condense evaporated refrigerant and controlled by the first and second named responsive means. 70
6. A refrigerating apparatus comprising a generator for a refrigerant, an evaporator, periodically operated means for heating the contents of the generator, control means including a pair of control members, means for locking said members together, means responsive to varying conditions within the evaporator to move said members simultaneously whereby the heating means is rendered operative, means responsive to varying conditions within the generator to unlock one of said members from the other whereby one of said members may be moved to render the heating means inoperative, cooling means for the contents of said generator, cooling means for condensing evaporated refrigerant, and operable means for directing a cooling medium to one or the other of said cooling means and depending for its operation on the one hand upon the operation of one of said responsive means and on the other hand upon the operation of the other of said responsive means. 80
7. A refrigerating apparatus comprising a generator for a refrigerant, an evaporator, periodically operated means for heating the contents of the generator, means for condensing evaporated refrigerant, control means including a pair of control members, means for locking said members together, means responsive to varying conditions within the evaporator, means controlled by said responsive means to move said members simultaneously whereby the heating means is rendered operative and to move one of said members into position to be locked to the other member after unlocking, means responsive to varying conditions within the generator to unlock said members whereby one of said members may be moved to render the heating means inoperative, and means controlled by the first and second named responsive means for periodically cooling the contents of the generator. 90
8. A refrigerating apparatus comprising a generator for a refrigerant, an evaporator, periodically operated means for heating the contents of the generator, means for cooling the contents of said generator, control means including a pair of control members, means for locking said members together, means responsive to varying conditions within the evaporator, means controlled by said responsive means to move said members simultaneously whereby the heating means is rendered operative and to move one of said members into position to be locked to the other member after unlocking, means responsive to varying conditions within the generator to unlock said members whereby one of said members may be moved to render the heating means inoperative, and means controlled by the first and second named responsive means for periodically cooling the contents of the generator. 100
- 115
- 120
- 125
- 130

generator to unlock said members whereby one of said members may be moved to render the heating means inoperative, and means periodically functioning to condense evaporated refrigerant and controlled by said responsive means.

9. A refrigerating apparatus comprising a generator for a refrigerant, an evaporator, periodically operated means for heating the 10 contents of the generator, control means including a pair of control members, means for locking said members together, means responsive to varying conditions within the evaporator, means controlled by said responsive means to move said members simultaneously whereby the heating means is rendered operative and to move one of said members into position to be locked to the other member after unlocking, means responsive to 15 varying conditions within the generator to unlock said members whereby one of said members may be moved to render the heating means inoperative, cooling means for the 20 contents of said generator, cooling means for condensing evaporated refrigerant, and operable means for directing a cooling medium to one or the other of said cooling means and depending for its operation on the one hand upon the operation of one of 25 said responsive means and on the other hand upon the operation of the other of said responsive means.

10. A refrigerating apparatus comprising a generator for a refrigerant, an evaporator, periodically operated means for heating the 30 contents of the generator, means for condensing evaporated refrigerant, means for cooling the contents of said generator, control means including a pair of oscillatory 35 control members, means carried by one of said members for locking said members together, means responsive to varying conditions within the evaporator to move said members simultaneously when locked together whereby the heating means is rendered operative, means responsive to varying 40 conditions within the generator and cooperating with the locking means to unlock one of said members from the other whereby one of said members may be moved to render the heating means inoperative.

11. A refrigerating apparatus comprising a generator for a refrigerant, an evaporator, periodically operated means for heating the 45 contents of the generator, means for condensing evaporated refrigerant, means for cooling the contents of said generator, control means including a pair of control members, means for locking said members together, means responsive to varying conditions within the evaporator to move said members simultaneously, and yieldable means placed under tension during simultaneous movement of said control members and adapted to cooperate with one of said

members to move it when unlocked from the other of said members whereby the heating means is rendered inoperative.

12. A refrigerating apparatus comprising a generator for a refrigerant, an evaporator, 70 periodically operated means for heating the contents of the generator, means for condensing evaporated refrigerant, means for cooling the contents of said generator, control means for the heating means including 75 a pair of movable control members, means for locking said members together, means responsive to varying conditions within the evaporator to move said members simultaneously whereby the heating means is rendered operative, unlocking means adapted to cooperate with the locking means, and means responsive to varying conditions within the generator and cooperating with 80 said unlocking means to unlock one of said members from the other whereby one of said members may be moved to render the heating means inoperative.

13. A refrigerating apparatus comprising a generator for a refrigerant, an evaporator, 90 periodically operated means for heating the contents of the generator, means for condensing evaporated refrigerant, means for cooling the contents of said generator, control means for the heating means including 95 a pair of movable control members, means for locking said members together, means responsive to varying conditions within the evaporator to move said members simultaneously whereby the heating means is rendered operative, unlocking means adapted to cooperate with the locking means, means responsive to varying conditions within the generator and cooperating with said unlocking means to unlock one of said members from the other whereby one of said members may be moved to render the heating means inoperative.

14. A refrigerator comprising a generator for a refrigerant, an evaporator, a periodically operated electrical heating element for heating the contents of the generator, means for condensing evaporated refrigerant, means for cooling the contents of said generator, control means for closing the circuit through said heater and including a pair of contacts one of which is adapted to be moved into engagement with the other and a pair of oscillatory control members, means carried by one of said members for locking said members together, means responsive to varying conditions within the evaporator to move said members simultaneously when locked together whereby one of 115

said contacts is moved into engagement with the other contact, means responsive to varying conditions within the generator and cooperating with the locking means to unlock one of said members from the other whereby one of said members may be moved and one of said contacts may be moved out of engagement with the other contact.

15. A refrigerator comprising a generator for a refrigerant, an evaporator, a periodically operated electrical heating element for heating the contents of the generator, means for condensing evaporated refrigerant, means for cooling the contents of said generator, control means for closing the circuit through said heater and including a pair of contacts one of which is adapted to be moved into engagement with the other and a pair of oscillatory control members, means carried by one of said members for locking said members together, means responsive to varying conditions within the evaporator to move said members simultaneously when locked together whereby one of said contacts is moved into engagement with the other contact, means responsive to varying conditions within the generator and cooperating with the locking means to unlock one of said members from the other whereby one of said members may be moved and one of said contacts may be moved out of engagement with the other contact, and yieldable means placed under tension during simultaneous movement of said control members and adapted to cooperate with one of said members to move it when unlocked from the other of said members.

16. A refrigerating apparatus comprising a generator for a refrigerant, an evaporator, a periodically operated means for heating the contents of the generator, means for condensing evaporated refrigerant, control means for the heating means including a pair of movable control members, means for locking said members together, means responsive to varying conditions within the evaporator to move said members simultaneously whereby the heating means is rendered operative, unlocking means adapted to operate with the locking means, means responsive to varying conditions within the generator and cooperating with said unlocking means to unlock one of said members from the other whereby one of said members may be moved to render the heating means inoperative, and means for periodically cooling the contents of the generator and depending for its operation upon the operation of the first and second named responsive means.

17. A refrigerating apparatus comprising a generator for a refrigerant, an evaporator, periodically operated means for heating the contents of the generator, means for cooling the contents of said generator, control means

for the heating means including a pair of movable control members, means for locking said members together, means responsive to varying conditions within the evaporator to move said members simultaneously whereby the heating means is rendered operative, unlocking means adapted to cooperate with the locking means, means responsive to varying conditions within the generator and cooperating with said unlocking means to unlock one of said members from the other whereby one of said members may be moved to render the heating means inoperative, and means periodically functioning to condense evaporated refrigerant and depending for its operation upon the operation of the first and second named responsive means.

18. A refrigerating apparatus comprising a generator for a refrigerant, an evaporator, periodically operated means for heating the contents of the generator, control means for the heating means including a pair of movable control members, means for locking said members together, means responsive to varying conditions within the evaporator to move said members simultaneously whereby the heating means is rendered operative, unlocking means adapted to cooperate with the locking means, means responsive to varying conditions within the generator and cooperating with said unlocking means to unlock one of said members from the other whereby one of said members may be moved to render the heating means inoperative, cooling means for the contents of said generator, cooling means for condensing evaporated refrigerant, and operable means for directing a cooling medium to one or the other of said cooling means and depending for its operation on the one hand upon the operation of one of said responsive means and on the other hand upon the operation of the other of said responsive means.

19. A refrigerator comprising a generator for a refrigerant, an evaporator, a periodically operated electrical heating element for heating the contents of the generator, control means for closing the circuit through said heater and including a pair of contacts one of which is adapted to be moved into engagement with the other and a pair of oscillatory control members, means carried by one of said members for locking said members together, means responsive to varying conditions within the evaporator to move said members simultaneously when locked together whereby one of said contacts is moved into engagement with the other contact, means responsive to varying conditions within the generator and cooperating with the locking means to unlock one of said members from the other whereby one of said members may be moved and one of said contacts may be moved out of engagement with the other contact, cooling means

- for the contents of said generator, cooling means for condensing the evaporated refrigerant, and operable means for directing a cooling medium to one or the other of said cooling means and depending for its operation on the one hand upon the operation of one of said responsive means and on the other hand upon the operation of the other of said responsive means.
- 10 20. A refrigerator comprising a generator for a refrigerant, an evaporator, a periodically operated electrical heating element for heating the contents of the generator, control means for closing the circuit through said heater and including a pair of contacts one of which is adapted to be moved into engagement with the other and a pair of oscillatory control members, means carried by one of said members for locking said members together, means responsive to varying conditions within the evaporator to move said members simultaneously when locked together whereby one of said contacts is moved into engagement with the other con-
- tact, means responsive to varying conditions 25 within the generator and cooperating with the locking means to unlock one of said members from the other whereby one of said members may be moved and one of said contacts may be moved out of engagement with 30 the other contact, yieldable means placed under tension during simultaneous movement of said control members and adapted to cooperate with one of said members to move it when unlocked from the other of 35 said members, cooling means for the contents of said generator, cooling means for condensing the evaporated refrigerant, and operable means for directing a cooling medium to one or the other of said cooling means 40 and depending for its operation on the one hand upon the operation of one of said responsive means and on the other hand upon the operation of the other of said responsive means.

In testimony whereof, I have affixed my signature to this specification.

ARCHIE HUGH STRONG.
